Application filed February 11, 1897. Serial No. 623,017. Term of patent 7 years.

To all whom it may concern:

Be it known that I, STANHOPE BOAL, residing at Piqua, in the county of Miami and State of Ohio, have invented a certain new and useful Design for a Stove or Range, of which the following is a specification.

My invention relates to a design for cooking stoves or ranges, the features of which will be more fully set forth in the description of the accompanying drawings, making a part of this specification, in which—

Figure 1 is a front elevation of a cooking stove or range, showing my design. Fig. 2 is a front elevation of the back plate of the shelf or closet, showing my design thereon.

The leading feature of my design consists of a raised scrollwork intertwined with raised network in the style of ornamentation known as "rococo;" also, raised scrollwork intertwined with raised barwork, which is a species of the same style of ornamentation. One of the features of my design consists in giving the scrollwork a shell-like form or configuration.

A represents the base-frame and legs of the stove or range. They are of curved swelling form, the outer surfaces of which are ornamented with scrollwork.

B represents the oven-door, which is of curved or swelling form, the outer surface of which is ornamented with raised scrollwork and preferably intertwined with network upon the lower corner.

C represents the reservoir-plate, the outer surface of which is ornamented with raised scrollwork and network intertwined.

D represents the side door, which is of swell or curved form and ornamented with raised scroll and net work intertwined.

E represents the front of the stove, consisting of the front plate, register-door, and top feed-door, which are all ornamented with the raised scrollwork of the style described in the manner shown.

D' represents the side plate of the stove, which is curved out flush with the oven-door and ornamented with the same style of design.

K represents the ash-pit plate, which is ornamented with the raised scroll design, as shown.

F represents a bracket attached to one side of the stove, which supports a shelf or closet. This bracket is ornamented with open-work, following the leading features of my design 55 already described, and preferably having bars and scrolls intertwined.

G represents the shelf supported on the bracket, ornamented with the shell form of 60 rococo design.

H represents the closet-doors, which are ornamented with the raised scrollwork, as shown.

I represents a railing around the top of the closet, which is ornamented with scrollwork, 65 as shown.

J represents the back plate of the shelf, which is ornamented with the scrollwork of the rococo style of ornamentation.

Having described my invention, I claim— 70
